Louis Barnett
ATTORNEY

UNITED STATES PATENT OFFICE

139,521

DESIGN FOR AN ORNAMENTATION TRANSFER SHEET FOR CHINAWARE OR THE LIKE

Therese Rita Gluck, Flushing, N. Y.

Application June 15, 1944, Serial No. 114,019

Term of patent 3½ years

(Cl. D59—2)

To all whom it may concern:

Be it known that Therese Rita Gluck, a citizen of the United States and resident of Flushing, Long Island, in the county of Nassau, State of New York, has invented a new, original, and ornamental Design for an Ornamentation Transfer Sheet for Chinaware or the like, reference being had to the accompanying drawing, forming part thereof, in which the figure is a plan view of an ornamentation transfer sheet for chinaware or the like embodying my new design.

I claim:

The ornamental design for an ornamentation transfer sheet for chinaware or the like, as shown.

THERESE RITA GLUCK.
